UNITED STATES PATENT OFFICE.

CLARENCE L. GREENING AND CHARLES W. GREENING, OF BRECKENRIDGE, MICHIGAN.

BEET HARVESTER.

Application filed May 24, 1920. Serial No. 383,833.

To all whom it may concern:

Be it known that we, CLARENCE L. GREENING and CHARLES W. GREENING, citizens of the United States, residing at Breckenridge, in the county of Gratiot and State of Michigan, have invented certain new and useful Improvements in Beet Harvesters, of which the following is a specification.

This invention relates to beet harvesters and the primary object of the invention is to provide an improved means for pulling the beets from the ground and elevating the beets for permitting the same to be conveniently harvested.

An object of the invention is to provide an improved means for receiving the beets from the puller and for throwing the beets on the elevating mechanism, the means for receiving the beets from the puller and for throwing the same on the elevator having means for driving the same at a relatively high rate of speed from the ground wheels.

A still further object of the invention is to provide an improved beet harvester of the above character which is exceptionally durable and efficient in use, one that is simple and easy to manufacture, and one which can be placed upon the market at a reasonable cost.

With these and other objects in view, the invention consists in the novel construction, arrangement and formation of parts as will be hereinafter more specifically described, claimed and illustrated in the accompanying drawings, forming a part of this specification, in which drawings:

Figure 1 is a side elevation of the improved beet harvester.

Figure 2 is a top plan view of the same.

Figure 3 is an enlarged fragmentary horizontal longitudinal section through the beet harvester showing a plan view of the beet puller and the means for receiving the beets from the puller and for throwing the same on the elevating mechanism.

Referring to the drawings, in detail, wherein similar reference characters designate corresponding parts throughout the several views, the letter A generally indicates the improved beet harvester, which includes a supporting frame B having a beet puller C arranged thereon, an elevating mechanism D, and a beet receiving and throwing means E for throwing the beets on the elevating mechanism D.

The frame B of the beet harvester includes

a pair of longitudinally extending side bars 10, which slightly converge toward their forward ends as clearly shown in Figure 2 of the drawings. The side bars 10 are connected at spaced points throughout their lengths by transverse cross braces 11 which serve to brace the frame throughout its entire length. The side bars 10 intermediate their ends carry the axle 12 which is mounted in suitable bearings 13 carried by the bars 10. The position of the arch axle 12 may be adjusted in the bearings in relation to the frame B by means of a lever and sector rack mechanism 14 which can be of the ordinary or any preferred construction. The outer ends of the arch axle 12 carry the relatively large ground wheels 15 which form the main support for the beet harvester. These wheels 15 carry relatively large sprocket wheels 16 which are utilized for driving the various parts of the beet harvester and if so desired these sprocket wheels may be connected to the ground wheels by suitable clutches so as to prevent the operation of the various parts of the beet harvester when the same is being driven to or from a field. The forward cross bar 11 supports any preferred type of draft appliance 17 which may be adjusted by a suitable lever and rack mechanism 18 which may be of the ordinary or any preferred construction. The side bars 10 intermediate their ends and adjacent to the bearings 13 have secured thereto the forwardly and downwardly inclined substantially U-shaped frame 19, which forms a portion of the beet pulling mechanism C which will be hereinafter more fully described. The bight portion 20 of the U-shaped frame 19 extends transversely across the frame B and supports a bracket 21 which pivotally carries a T-shaped rod 22, the rearwardly extending leg of which supports the operator's seat 23. The outer ends of the arms of the T-shaped rod 22 have suitable links 24 connected thereto which extend toward the forward end of the machine. The bars 10 adjacent to their forward ends carry suitable bearings 25 in which are mounted vertically disposed shafts 26 the lower ends of which carry the gauge wheels 27. The upper ends of the shafts 26 carry the crank arms 28 and these crank arms have attached thereto the connecting rods 24. Thus it can be seen that by swinging the seat 23 the gauge wheels 27 can be swung so as to guide the machine and hold the same

in correct alignment with the row of beets being harvested.

As stated, the U-shaped frame 19 forms a part of the beet pulling mechanism C and the legs of the U-shaped frame gradually converge toward their lower ends as clearly shown in Figures 2 and 5 of the drawings. The terminals of the legs of the U-shaped frame 19 have feet 29 formed thereon which have bolted or otherwise secured thereto the puller bars 30. The pulling bars 30 are inclined upwardly and rearwardly, so that as the bars engage the beets the same will be gradually raised out of the ground without bruising the beets in any way whatsoever. The forward lower ends of the pulling bars or plows 30 gradually diverge so that if the beets are not in direct alignment, the bars or plows will guide the same toward the central portion thereof. The forward ends of the pulling bars or points are sharpened and tapered as at 31.

The elevating mechanism D for the beets includes a lower frame 32 which consists of rearwardly and downwardly extending side bars 33, which are strapped or otherwise secured to the legs of the U-shaped frame 19 adjacent to their lower ends. The side bars 33 carry at their lower ends a shaft 34 and this shaft is located directly in rear of and slightly spaced from the pulling bars 30. The shaft 34 adjacent to its terminals is provided with sprocket wheels 35 which are in direct alignment with sprocket wheels 33 carried by an upper shaft 36, which is mounted in suitable bearings 37 carried by the longitudinally extending side bars 10. The aligned sprocket gears receive the drive sprocket chains 38 which form a portion of the endless conveyor belt 39 which is used for elevating the beets. The chains 38 are connected by transversely extending slats 40 and certain of these slats carry flights or the like 41 for preventing slipping of the beets on the belt.

The means E for receiving the beets from the puller C and throwing the same on the conveying mechanism D are arranged intermediate the pulling mechanism C and the elevating mechanism D and include a substantially upwardly extending U-shaped frame 43 which is connected to the side bars 10. The frame 43 extends slightly above the side bars 10 and forms a support for the lever and rack mechanism 18. The legs of the U-shaped frame 43 converge toward their lower ends and engage the legs of the U-shaped frame 19 and the terminals of the legs of the U-shaped frame 43 have secured thereto the downwardly and forwardly inclined side bars 44, which rotatably support a shaft 45. This shaft 45 extends directly above and in rear of the pulling bars 30 and has mounted thereon a plurality of radially extending prongs or teeth 46 which are

adapted to stick into the beets and throw the same onto the elevating mechanism.

The elevating mechanism D and the beet receiving and throwing mechanism E are operated from the ground wheels 15 and these means include a transversely extending shaft 47 which is mounted in suitable bearings carried by the side bars 10 forwardly of the ground wheels. The terminals of the shaft 47 carry suitable sprocket wheels 49 which are in alignment with the relatively large sprocket wheels 16 carried by the ground wheels 15. The sprocket wheels 49 and 16 have trained around the same drive sprocket chains 50. The shaft 47 has also keyed thereto a sprocket wheel 51, which is in direct alignment with a sprocket wheel 52 keyed to a stub shaft 53' which is rotatably mounted in a bearing 47. This stub shaft 53' has keyed thereto a gear wheel 53 which is in mesh with a gear wheel 54 keyed to the shaft 36 which supports the upper end of the conveyor belt 39. Thus it will be seen that when the machine is in motion power will be transmitted from the ground wheels to the shaft 36 for operating the endless belt 39. The U-shaped frame 43 supports a pair of superposed transversely extending shafts 55 and 56 and the uppermost shaft 55 has keyed thereto a sprocket wheel which is in alignment with a sprocket wheel carried by the counter shaft 47 and these sprocket wheels have trained around the same a sprocket chain 57. The shaft 55 has keyed thereto a gear wheel 58 which is in mesh with a gear wheel 59 keyed to the lower shaft 56. The lower shaft 56 has keyed thereto a sprocket wheel which is in direct alignment with a sprocket wheel keyed on to the shaft 46 carried by the side bars 44, and these sprocket wheels have trained around the same a drive sprocket chain 60. Thus it will be seen that when the machine is in motion the power will be transmitted from the ground wheels 15 to the lower shaft 46 for driving the beet receiving and throwing mechanism E.

In operation of the improved beet harvester, the same is driven to the field, where the beets are to be harvested, and the pulling bars 30 are forced into the ground. The machine is then started and as the inclined bars 30 engage the beets, the same will be gradually pulled upwardly from the ground. As soon as the same reach the upper ends of the inclined bars the outwardly extending teeth or prongs 46 will stick into the same and throw the beets rearwardly onto the upper surface of the endless belt 39 which will carry the same to a beet dumping and collecting mechanism. When it is necessary to guide the machine so as to hold the same in direct alignment with the beets being harvested, it is merely necessary to move the seat 23 which will operate the

cranks 28 for rotating the shafts 26 for turning the guide wheels 27. Owing to the means of connecting the beet receiving and throwing mechanism with the drive wheels 5 15 the same will be rotated at a relatively high rate of speed so that sufficient momentum will be given to the beets for throwing the same on the conveyor mechanism.

From the foregoing description, it can be 10 seen that an exceptionally simple beet harvester has been provided which will perform the service intended in a durable and efficient manner.

Changes in details may be made without 15 departing from the spirit or scope of the invention; but,

We claim:

1. In a beet harvesting device, a frame, a pair of ground wheels for the frame, a depending U-shaped frame secured to the supporting frame, a pair of inclined pulling bars carried by the lower terminals of the U-shaped frame, an elevating mechanism carried by the supporting frame and including 20 an endless belt and supporting shafts therefor, a second depending U-shaped frame carried by the supporting frame, side bars carried by the terminals of the second U-shaped frame, a rotatable shaft carried by 25 the side bars, arcuate penetrating teeth carried by the shaft and extending radially therefrom, said shaft being arranged intermediate the pulling bars and the conveyor belt, and means for operatively connecting 30 the ground wheels with the conveyor belt supporting shafts and with the rotatable shaft carried by the side bars.

2. In a beet harvester, a supporting frame, ground wheels carried by the frame, relatively large drive sprocket wheels carried by the ground wheels, a downwardly and forwardly extending U-shaped frame carried by the supporting frame, pulling plow bars carried by the terminals of the U-shaped frame, rearwardly and downwardly inclined side bars carried by the U-shaped frame, a cross shaft carried by the side bars, an upper cross shaft carried by the supporting frame, sprocket wheels secured to the shafts, 40 drive sprocket chains trained around said sprocket wheels, transversely extending slats connecting said sprocket chains, a second depending U-shaped frame carried by the supporting frame in advance of the first 45 U-shaped frame, said U-shaped frames being connected together adjacent to their lower ends, forwardly extending side bars carried by the terminals of the second mentioned U-shaped frame, a rotatable shaft carried by 50 the last mentioned side bars, arcuate radially extending penetrating prongs carried by the

rotatable shaft, a counter-shaft carried by the supporting frame, sprocket wheels keyed to the terminals of the counter-shaft, drive chains trained around the sprocket wheels carried by the counter-shaft and the drive wheels, a pair of transversely extending shafts carried by the second mentioned U-shaped frame, means operatively connecting the shafts together, means operatively 65 connecting the uppermost shaft with the counter shaft, means operatively connecting the lowermost shaft with the shaft carrying the penetrating prongs, and means operatively connecting the uppermost supporting 70 shaft for the conveyor belt chains with the counter-shaft.

3. In a harvesting device, a main frame, a forwardly and downwardly extending supplemental frame carried by the main frame, a pair of pulling bars carried by the lower end of the supplemental frame, an inclined elevating mechanism arranged in rear of and above and in spaced relation to the pulling bars, downwardly and forwardly inclined side bars arranged intermediate the supplemental frame and the elevating mechanism and in substantially parallel relation to the supplemental frame, clamps for 80 adjustably holding the side bars in position, and a rotatable vegetable receiving and throwing mechanism carried by the side bars.

4. In a harvesting device, a supporting frame, ground wheels carried by the frame, a downwardly and forwardly extending U-shaped frame carried by the supporting frame, pulling side bars carried by the terminals of the U-shaped frame, rearwardly inclined side bars arranged on opposite sides 95 of the U-shaped frame, clamps engaging the side bars and the U-shaped frame, a cross shaft carried by the side bars, an upper cross shaft carried by the supporting frame, sprocket wheels secured to the shafts, an elevating belt carried by the sprocket wheels, the cross shaft carried by the side bars being arranged above the surface of the ground, and in rear of and in spaced relation to the upper rear terminals of the plow bars, and a second depending U-shaped frame 100 arranged intermediate the first mentioned U-shaped frame and the elevating belt, adjustable clamps for securing the second U-shaped frame in operative position in relation to the beet pulling bars and the elevating belt, a shaft carried by the second mentioned U-shaped frame, and a plurality of radially extending longitudinally spaced fingers carried by the last mentioned shaft.
